UNITED STATES PATENT OFFICE.

DE WITT C. COOKINGHAM, OF LAKEWOOD, OHIO, ASSIGNOR TO THE BAKER R. & L. COMPANY, OF CLEVELAND, OHIO, A CORPORATION OF OHIO.

DESIGN FOR A MEASURING-INSTRUMENT CASE.

49,052.

Specification for Design.

Patented May 16, 1916.

Application filed September 22, 1915. Serial No. 52,122. Term of patent 3½ years.

To all whom it may concern:

Be it known that I, DE WITT C. COOKINGHAM, a citizen of the United States, and resident of Lakewood, county of Cuyahoga, and State of Ohio, have invented a new, original, and ornamental Design for Measuring-Instrument Cases, of which the following is a specification, reference being had to the accompanying drawing, forming part thereof.

In said annexed drawing:—Figure 1 is a front elevation, and Fig. 2 is a side eleva-

tion of a measuring instrument case, showing my new design.

I claim:—

The ornamental design for a measuring instrument case, as shown.

Signed by me this 21st day of September, 1915.

DE WITT C. COOKINGHAM.
